CLAIM

I claim the ornamental design for a food container, as shown and described.

(30) **Foreign Application Priority Data**

DESCRIPTION

Aug. 16, 2010 (EP) 001229884

FIG. 1 is a top view of a food container according to a first embodiment of my new design;

(51) **LOC (10) Cl.** **09-03**

FIG. 2 is front view thereof, the rear view being a mirror image thereto;

(52) **U.S. Cl.**

FIG. 3 is a right side view thereof, the left side view being the same;

USPC **D9/425**

FIG. 4 is a bottom view thereof;

(58) **Field of Classification Search**

FIG. 5 is a top view of a food container according to a second embodiment of my new design;

USPC D9/414, 419, 424, 425, 431, 432, 435;
D7/601-603, 605, 629; 220/23.4, 23.6,
220/266, 281, 315, 318, 659, 696, 752, 760,
220/790, 793; 229/105, 117.09, 117.26,
229/189, 406; 206/508; D3/276

FIG. 6 is front view thereof, the rear view being a mirror image thereto;

See application file for complete search history.

FIG. 7 is a right side view thereof, the left side view being the same; and,

(56) **References Cited**

FIG. 8 is a bottom view thereof.

U.S. PATENT DOCUMENTS

The broken line portion of the drawings is included to show unclaimed subject matter only and forms no part of the claimed design.
